UNITED STATES PATENT OFFICE.

ASBIA B. FITCH, OF CHICAGO, ILLINOIS.

HOLDER FOR CONDUCTORS' CHECKS OR TICKETS.

1,321,815.

Specification of Letters Patent.

Patented Nov. 18, 1919.

Application filed February 20, 1919. Serial No. 278,206.

To all whom it may concern:

Be it known that I, ASBIA B. FITCH, a citizen of the United States, residing at Chicago, in the county of Cook and State of Illinois, have invented certain new and useful Improvements in Holders for Conductors' Checks or Tickets, of which the following is a specification.

My present invention relates to improvements in a holder for tickets or checks, such as are used by railway conductors, to indicate that they have taken up, examined, or punched the regular railroad or passenger tickets of passengers, and to show to the conductor, at a glance, the destination of passengers, and has for its objects somewhat similar objects to those set forth in Letters Patent of the United States No. 1,060,072, granted to me on the 29th day of April 1913, for a holder of a similar class, to-wit, to provide holders for the above mentioned purpose, which shall be simple and inexpensive in construction, strong, durable, attractive in appearance and efficient in operation, which shall be so made as to be especially adapted to be mounted on and supported by the hollow rods of the shades of car windows and in front of the shades within view and easy reach of both the conductor and passenger, yet so as not to interfere with the raising or lowering of the shades, or be concealed thereby when the shades are raised, for, as is well known said rods are located horizontally on the lower portions of such shades a slight distance from the lower ends thereof, and carry spring-actuated rods having on their outer ends means to engage vertical grooves in the window frame for the purpose of guiding the shades in their upward and downward movements and for holding them at desired points.

Another object is to provide holders having clamping portions between which the conductor may readily place one or more tickets or checks where they will be held without danger of being jarred out by the vibration of the cars, or blown out by drafts or otherwise accidentally dislocated. Numerous other objects and advantages of the invention will be disclosed in the subjoined description and explanation.

The invention consists in certain peculiarities of the construction, novel arrangement

and operation of the various parts thereof as will be hereinafter more fully set forth and specifically claimed.

In the accompanying drawing, which serves to illustrate the invention—

Figure 1 is a fragmental face view of a portion of a shade for car windows showing my improved holder for checks or tickets mounted thereon and supported by the hollow rod of the window shade;

Fig. 2 is a greatly enlarged cross sectional view taken on line 2—2 of Fig. 1 looking in the direction indicated by the arrows;

Fig. 3 is an inner face view of one of the clamping members or portions of the holder, and

Fig. 4 is a detached perspective view of a clip used to secure the front part of the holder to the front surface of the shade and to support the holder on the hollow rod of the shade.

Like numerals of reference refer to like parts throughout the different views of the drawing.

The reference numeral 5 designates a part of the lower portion of a shade for car windows, which shades are mounted on a self acting winding roller located horizontally in the upper portion of the window frame in the well-known way. Such shades are provided at a slight distance from their lower ends with horizontally disposed hollow rods 6, in which are located spring actuated rods 7, having on their outer ends means to engage the sides of the window frames for the purpose of guiding the shades in their upward and downward movements, as well as for holding them at desired points. At its lower edge each of the shades is provided with a loop 8, in which is located another and smaller rod 9, used for reinforcing the lower portions of the shades. The main or body portion 10 of the holder consists of a single piece of metal substantially rectangular in shape, but somewhat elongated, as shown in the different views of the drawing, and is bent back upon itself at its lower portion, thus forming a loop 11, which possesses some resiliency, and from which is upwardly extended an outer clamping member 12, which lies close to or against the front surface of the other clamping member 13 of the holder. The main or body portion 10 of the holder is outwardly and downwardly

curved as at 14, from a suitable point below the upper end of said portion in order to embrace and lie on a portion of the rod 6 of the shade and against the front surface of the latter. As shown this bent portion of the body part 10 describes an arc of about one-quarter of a circle, and the body portion is extended from the lower part of said curved portion downwardly in a vertical line or in a parallel plane with the straight upper part of the body portion. The clamping member 12 by preference has its upper end rounded as shown at 15 in Fig. 1, and is located along the curved portion 14 of the body portion 10, which location will produce an open space 16 between the members 12 and 13 for the insertion of the tickets 17 or checks. The upper portion of the member 10 is provided with an opening 18 and the lower portions of the members 12 and 13 are provided with registering openings 19, which openings are for the reception of rivets 20 employed for securing the said members, as well as a supporting clip 21 to the shade 5 and around the hollow rod 6 of the shade. The clip 21 has near each of its ends an opening 22 for the reception of the rivets 20 and said clip is provided between said openings with an outwardly curved portion 23, which is substantially semi-circular in shape as shown.

The inner surface of the outer clamping member 12 is provided with a series of projections 24 arranged in curved rows, one above the other, as is clearly shown in Figs. 1 and 2 of the drawing. These projections are by preference formed by indentations produced on the outer surface of said member, and said projections are also by preference located in one row in staggered relation to those in the other row. The inner surface of the clamping member or part 13 of the body portion 10 is provided with projections 25 arranged in transverse rows as shown in Fig. 3, which rows are located about the same distance apart as the curved rows in the front clamping member 12, and the lower transverse row is located at about the lower ends of the curved rows, while the upper row is located at about the top of the lower curved row.

From the foregoing and by reference to the drawing, it will be readily understood and clearly seen that as the clamping portions 12 and 13 are secured together by a rivet 20, located some distance below the upper end of the clamping member 12, the upper portion of said member will be free to be sprung outwardly slightly by the insertion of tickets 17 between the rounded portion 14 of the body part 10 and the upper portion of the member 12, and that by reason of the inherent resiliency of the member 12, as well as that imparted thereto by the spring loop 11 the tickets or checks

will be securely held in position, yet in such a manner that one of them can be withdrawn without the removal of the other or others. It is obvious that the projections 24 and 25 on the clamping portions of the holder will provide positive gripping or holding means for the tickets or checks.

It is further manifest that the rivet 20 which holds the lower portions of the clamping members 12 and 13 and the lower part of the clip 21 together may be of sufficient length between its heads 26 to allow slight movement of the member 12 toward and from the member 13 incident to the action of the loop 11 or spring. It will also be understood that by making the curved portion 14 of the body part 10 of about the size of one-quarter of a circle, and by making the rearwardly curved part of the clip 21 of about semi-circular form with a lateral extension 27, the member 13 of the body portion will be located and held in an offset plane parallel to the body portion of the shade, thus allowing the lower portion 28 of the shade to hang down in front of the window sill, while the lower portion of the shade surrounding the roller will rest on said sill, thus excluding light from the window when desired.

Having thus fully described my invention what I claim as new and desire to secure by Letters Patent is—

1. A holder for tickets or checks consisting of a main or body portion having its lower portion extended back upon itself thus forming a front and a rear clamping member and provided above the free end of said front member with a forwardly curved portion and a vertical apertured extension above said curved part, and a clip having a rearwardly curved portion between its ends and secured to the rear surface of the body portion above and below the said curved parts thereof.

2. A holder for tickets or checks consisting of a main or body portion having its lower portion extended back upon itself thus forming a front and a rear clamping member and provided above the free end of said front member with a forwardly curved portion and a vertical apertured extension above said curved part, said front and rear members having on their inner surfaces a series of projections, and a clip having a rearwardly curved portion between its ends and secured to the rear surface of the body portion above and below the said curved parts thereof, said curved portion of the clip being extended at its lower part to a vertical line alongside the depending portion of the main or body part of the holder.

3. A holder for tickets or checks consisting of a main or body portion having its lower part extended back upon itself thus forming a front and a rear clamping mem-

ber and provided above the free end of said front member with a forwardly curved portion, said front and rear members having on their inner surfaces a series of projections, the projections on the front member being arranged in circular rows and in staggered relation, and a clip having a rear-

wardly curved portion between its ends and secured to the rear surface of the body portion above and below the said curved parts 10 thereof, said curved portion of the clip being greater than the said curved portion of the body part.

ASBA B. FITCH.
